Group

(30) **Foreign Application Priority Data**

(57) **CLAIM**

Jan. 10, 2002 (JP) 2002-000378

The ornamental design for a vehicle wheel, as shown and
described.

(51) **LOC (7) Cl. 12-16**

DESCRIPTION

(52) **U.S. Cl. D12/211**

FIG. 1 is a perspective view of a vehicle wheel showing my
new design;

(58) **Field of Search** D12/204-211;
301/37.101, 64.101, 65

FIG. 2 is a front elevational view thereof;

(56) **References Cited**

FIG. 3 is a top plan view thereof;

U.S. PATENT DOCUMENTS

FIG. 4 is a bottom plan view thereof;

D208,543 S * 9/1967 Halibrand D12/211

FIG. 5 is a left side elevational view thereof;

D361,976 S * 9/1995 Echazabal et al. D12/211

FIG. 6 is a right side elevational view thereof;

D396,208 S * 7/1998 Baumgartner et al. D12/211

FIG. 7 is a sectional view taken along a line 7—7 shown in
FIG. 2; and,

D418,473 S * 1/2000 Chung D12/211

FIG. 8 is a sectional view taken along a line 8—8 shown in

D446,180 S * 8/2001 Sulahian et al. D12/211

FIG. 2.

D448,712 S * 10/2001 Laengerer D12/209
